DESIGN FOR A DISPLAY HANGER OR SIMILAR ARTICLE

Una Nash, Astoria, N. Y.

Application January 30, 1939, Serial No. 82,672

Term of patent 3½ years

To all whom it may concern:

Be it known that I, Una Nash, a citizen of the United States of America, residing in Astoria, in the Borough of Queens, county of Queens, and State of New York, have invented a new, original, and ornamental Design for a Display Hanger or Similar Article, of which the following is a specification, reference being had to the accompanying drawing, forming part thereof, wherein.

I claim:

The ornamental design for a display hanger or similar article, substantially as shown.

UNA NASH.
